ATTORNEY

UNITED STATES PATENT OFFICE.

FRANK T. KOVAR, OF CLEVELAND, OHIO.

FUSE BLOCK.

Application filed September 13, 1924. Serial No. 737,508.

This invention relates to improvements in fuse blocks or cut-outs for electrical work, the blocks being designed to be used in the usual panel boxes.

It is an object of my invention to devise a fuse block that can be readily assembled in panel boxes so that the number of said blocks may be increased or decreased to vary the size of the panel desired.

It is a further object of my invention that the nature of these blocks render them readily accessible not only for mounting individual blocks, but also to replace parts of an individual block without replacing parts not needing repair.

It is a particular advantage of my construction that each fuse block is made in two parts or sections, one superposed upon the other, only the upper part in the great majority of cases needing removal or replacement. This results in a very economical and simple structure.

It is a still further object of my invention to make my fuse blocks of superposed sections, only the lower section being connected to the bus bars, and the upper section carrying the fuse sockets.

It is a further object of my invention to provide fuse blocks for panel boxes, which are made in superposed sections, the upper section being readily replaceable without disengaging the lower section from the box.

With these and other objects in view the detailed structure of my improvement will appear in the following specification, the novel features particularly pointed out in the appended claims and the invention illustrated in the accompanying drawings forming a part of the application, in which,

Figure 1 is a view showing in plan the manner of assembling the fuse blocks in a panel box, a portion of the cover section of an end block being removed;

Figure 2 is a front elevation with one end in longitudinal section, of one of the intermediate blocks according to my invention, and

Figure 3 is a view of an end block showing in elevation, the superposed sections in position and the ends of the bus bars connected with wire connectors, a copper plate for connection with various branches being shown in dotted lines.

Referring to the drawings, 10 designates the main fuse blocks which are arranged in a de-

sired number in a single panel form the body of the series, and 11 is an end block at the upper and lower end of the series and the entire set secured to the base of the panel box in the usual manner. Since the nature of my invention is not particularly concerned with the particular character of the box in which the set is to be secured, no detailed description will be given of the box, merely assuming that the various blocks will be arranged in the order illustrated in Fig. 1 of the drawings, and suitable arrangements provided for leading outside conductors through the panel walls for connection with the various parts that will be herein described.

Referring to Fig. 2, it is to be noted that the block 10, comprises a base section 12 having legs 13 and an intermediate leg 14, the latter having a vertical aperture 15 leading upward to an enlarged opening 16 designed to receive a screw for attaching the base 12 to the suitable support, usually the base of a panel box. It is to be noted as an especial advantage of my construction that the head of the screw is retained in this cavity 16, there being no need for the screw head projecting into the cover part 17 of the block.

The bus bars 18 are secured to the lower surface of the base member by screws 19, the same being sheltered in the arch between the legs 13 and 14. The bus bars 18 extend substantially the length of the panel, terminating just beyond the screw 19 of the last main block at the top of the panel, and extending down into the lower end block, as will be later described more in detail.

Each main block 10 is provided with two spaced fuse sockets 20 which are provided in the cover section 17 only, so that when the cover is removed, the sockets are carried with it; and unless the intermediate blocks are used in some special arrangement, the base sections 12 of these blocks may remain in position, while the covers 17 are removed. This will be found to be a great advantage where certain intermediate blocks of a panel are desired to be unused temporarily, though it may be desirable at some further time to put them into commission.

For the reason above given the bottom of the socket in the cover member is provided with a slightly raised portion 21 having a vertical aperture through which the screw 19 extends with the head 22 resting upon the projection 21, as the screw is inserted through

both sections and threaded into the bus bar 18 below. Thus the screw 19 not only serves as an electric conductor between the base of the fuse socket and the bar, but also serves as the sole means for securing the sections of the block together. To further utilize the advantages of this structure, the lower edge of the socket 20 is bent radially inward to form an integral annular flange 23 separated from the head 22 by the insulating material of the cover section, and the ends of the latter are provided with raised portions 24 separated by trough shaped slots 25 in which are seated conductor strips 26 whose inner ends extend back to a point beneath the flange 23 which parts are connected together detachably by a screw 27. A special advantage of this detail consists in the fact that the strips 26 are also carried by the cover 17, whereby when the screws 19 are removed, the cover may be lifted off carrying with it the fuse sockets and the conducting strips 26. The outer ends of the latter are provided with binding screws 28.

Any desired number of these intermediate blocks 10 may be provided and positioned in parallelism to the approximate capacity of the panel box in which they are to be mounted. It is desirable in any case to provide end blocks 11, no matter how large a number of the blocks 10 is used. The block 11 also comprises base and cover sections 29 and 30, respectively, the base section having the apertures 15 and 16, just as in the base 12. It has however an elongated deep depression 31 separated into further depressions 32 by an intermediate raised portion 33. The central screw is also used in this section for securing the entire block to the panel base, but the end construction of 29 differs from 12 in that the slotted end construction of the block is in the base section rather than in the cover. See the parts 34' separated by the trough 35', in Fig. 1. The lower surface of the section 29 is flat and smooth. The section 30 is bridge-shaped, the inner surface being hollowed out somewhat at 36. The upper surface is also smooth, the ends of sections 29 and 30 being secured together by screws 37. Between these sections, therefore, is a large opening or cavity that may be utilized for different purposes. When used at the upper end of the panel, a perforated plate 38 of conducting material is of a length adapted to bridge the shoulders 39 on the lower section 29 and to which it is secured by fastening the middle portion of the plate 38 to the portion 33 by screws 40. Other binding screws 41 are fastened to the plate in position to readily secure ends of conductors thereto. A projecting tubular connector 42 is secured to the end of the plate by screw 43 and is positioned in alinement with the slots 35' when the plate is in position. The fastening of the cover 30 over this plate will then protect the latter

from accidental contact with the main conductors.

When blocks 11 are used at the bottom end of the panel, the plate 38 is removed therefrom by removing the screws 40, and while the cover 30 is omitted the base is secured in position on the panel base with the lower ends of the bus bars overlapping the depressions 32, so that the tubular connectors 44 on the ends of the bars may aline with the slots 35', as shown in the drawings. The cover 30 may then protect the connections between the parts 18 and 44.

In assembling the blocks in a panelboard, end blocks 11 are arranged as shown in Fig. 1, though the base 29 is shown in that view reduced in width. The panel in Fig. 1 shows two intermediate blocks 10, only the upper one being in commission. The operation of the arrangement will however be clear as now described. The covers 30 are removed until the bases 29 of the end blocks are secured to the panel by screws passing through the apertures 15, the heads of these screws remaining in the cavities 16 and not entering any portion of the upper section 17. Assuming now, that ten blocks 10 are to be used of which number but seven are to be placed immediately in commission, the other three not being used until there is a future need for them: The bases 12 of the three unused blocks will be secured in position just the same as the others, but the covers will be omitted.

Covers 17 with fuse sockets, as shown, and carrying the strips 26 secured to the bottom of the sockets by the screws 27, will now be applied to the seven blocks now to be wired, and the bus bars 18 will be placed underneath all of the base sections 12, their ends extending into the sockets 32 of the base section 29 of the lower block 11. Screws 19 will now be inserted in the fuse sockets of the seven blocks 10 and are screwed down into engagement with the bars 18, thus securing the sections together as well as providing electrical connection between the sockets and the bar. No such connection will be made for the three blocks out of commission.

For three wire service, conductors are led into the slots 35' to the tubular connectors 44 in the block 11 at one end, and another conductor is led in through the slot 35' of the upper section 11 and connected with the tube 42. I therefore have three conductors 44, 42 and 44. Connections can now be made for any branch by leading one conductor from a suitable screw 41 of the plate 38 and another conductor from one of the screws 28 of a plate 26. Suitable fuse plugs will now be screwed

into the sockets 20 making connection between the strip 26 and the bar 18, completing the circuit.

For two wire circuits, branches from the tubes 44 are connected together and to a conductor from one pole, and the other conductor connected with the tubular connector 42. The branch connections are made as in three-wire service.

10 It is therefore seen that no fuse sockets are provided for the vacant blocks, the latter having no connection whatever with the others, other than being assembled ready for use when the cover sections with their 15 sockets and strips 26 are attached. Small sockets may be provided in the upper surface of the section 12 to receive the lower ends of the screws 27 and 28, if it is desired. Further, a shallow depression may be formed in 20 the same surface to permit the plate 26 to sink thereinto when the cover is applied, such a structure tending to make the connection between the sections more certain and stable.

It will now be seen that my sectional blocks 25 make adjustability of panels to varying capacity very easy, and make it especially easy to throw the vacant blocks into commission without making any change in the bus bars other than inserting the screws 19 when the 30 socket sections are applied. It is to be noted that the cover presents no connecting device other than the plugs and the binding screws 28, the screws for securing the blocks to the panel base not appearing above the cover.

35 It is a special feature of my construction that only the upper section in the great majority of cases will need removal or replacement, which renders the device exceedingly economical and simple. If a unit needs repair, the 40 cover may be removed by merely withdrawing the screws 19 when it can be repaired or replaced by a new one. The screws for fastening the lower section to a support may remain indefinitely, and if this particular unit 45 should not be needed, the fuse sockets may be removed altogether without making any change in the bus bars. These changes will not require special tools for the purpose, only the usual screw driver for connecting parts 50 together.

55 My structure is one susceptible of molding the individual sections of suitable insulating material, as will be understood, thus rendering its commercial manufacture economical and rapid.

Having thus described my invention, I claim as new and desire to secure by Letters Patent:

1. A fuse block having superposed elongated sections of equal length detachably connected together, the base section having spaced bus bars extending thereunder and across its axis and means between said bars for securing the base section to a support, and 60 a cover section concealing said securing

means, said cover section carrying a fuse socket and a connector element extending laterally from said socket.

2. A fuse block of the character described comprising an integrally-molded cover section detachable from an integrally-molded base section, the latter having means for securing the same to the bottom wall of a box, and carrying spaced bus bars for connection with corresponding base sections of other 70 blocks of a series, the several cover sections each carrying fuse sockets and lateral connecting members, and means serving for detachably connecting the sections of each block together and for conductively connecting a 75 socket with a bus bar.

3. A fuse block having superposed integral sections of equal length, the base section having bus bars positioned thereunder, and the cover sections carrying fuse sockets symmetrically arranged thereon and connecting members leading to said sockets, and securing means of conducting material passing through the bottoms of said sockets and through the said block sections for detachable engagement with said bars for securing 85 the sections together.

4. A fuse block comprising superposed sections of equal length, the base section carrying spaced bus bars underneath and the cover section carrying fuse sockets thereon and connector elements extending laterally therefrom, underneath said cover section, means passing through said base section between 90 said bars for securing the base block to the 95 bottom of a panel box, and conducting means, passing through both sections, detachably securing the bottom of the fuse sockets directly to the bus bars, respectively.

5. A fuse block comprising superposed detachable sections, the base section having three lower supports spaced apart, there being a vertical aperture through the intermediate supports for receiving means therein for securing the block to a panel base, the 100 cover section carrying spaced fuse sockets 110 therein, the latter being in registry with apertures through the base section to receive connectors therethrough for securing bus bars 115 therebeneath, and conducting means extending laterally from said sockets and provided with binding connectors.

6. In a panel box, the combination of a series of fuse blocks, each block comprising superposed detachable sections, the base sections of each block having means for securing the same separately to a suitable support and carrying spaced bus bars thereunder extending across the base sections of the series, the cover sections carrying fuse sockets, and conducting means passing through the sections of each block and detachably connecting each 120 socket with a bus bar therebeneath.

7. In a panel box, the combination of a series of fuse blocks each block comprising 125

superposed detachable sections, the base section of each block having means for securing the same to the base of the box, and carrying spaced bus bars thereunder extending longitudinally of the box, the several cover sections carrying fuse sockets thereon, the sections of each block having apertures therethrough extending from the bottom of the sockets of the cover sections to the bars underneath the base sections, and securing means in said apertures for removably securing the sections together and the said sockets to the bars, whereby the bus bars and the base sections may remain in position while the cover sections and their fuse sock-

ets are being removed for repair or replacement.

8. An elongated fuse block, comprising a base section having bus bars carried thereunder, a cover section superposed upon, detachably secured to and of the same length as said base section, said cover section carrying spaced fuse sockets, electrically and mechanically connected with said bus bars, and connecting members electrically connect- 20 25 ed with said sockets.

In testimony whereof I hereunto affix my signature.

FRANK T. KOVAR.
